MOUNTING RECEPTACLE FOR AN AUTOMOBILE DIRECTIONAL SIGNAL LIGHT FLASHER OR SIMILAR ARTICLE

John B. Dickson, Kew Gardens, N.Y., assignor to Signal-
Stat Corporation, Brooklyn, N.Y., a corporation of New
York

Filed July 27, 1961, Ser. No. 66,093

Term of patent 14 years

(Cl. D26—1)

FIG.1

FIG.2

FIG.3

FIG.4

FIG.5

FIG.6

FIG. 7

FIG. 8

FIG. 1 is a rear end elevational view of a mounting receptacle for an automobile directional signal light or similar article, embodying my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof; and

FIG. 8 is a rear perspective view thereof.

I claim:

The ornamental design for a mounting receptacle for

an automobile directional signal light flasher or similar article, substantially as shown.
